UNITED STATES PATENT OFFICE.

CHARLES HROMAS AND FRANK MACH, OF DAVID CITY, NEBRASKA.

TRANSOM-LIFTER.

SPECIFICATION forming part of Letters Patent No. 392,560, dated November 6, 1888.

Application filed May 28, 1888. Serial No. 275,409. (Model.)

To all whom it may concern:

Be it known that we, CHARLES HROMAS and FRANK MACH, citizens of the United States, residing at David City, in the county of Butler and State of Nebraska, have invented certain new and useful Improvements in Transom Lifter and Lock Combined; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in transom-lifters; and it consists in a certain novel arrangement and combination of parts, as will be hereinafter more fully set forth in the specification, and pointed out in the claim.

The object of the invention is to construct a device which can be more readily operated than those heretofore in use and with less effort, and at the same time to present a device which will be of attractive appearance.

Another object of our invention is to construct a device which will be simple and not liable to get out of order, and which will at the same time be inexpensive to manufacture.

In the accompanying drawings, forming a part of this specification, and on which similar letters of reference indicate the same or corresponding features, Figure 1 is a front view of our improved device applied to the door-frame and transom and showing the latter partly open. Fig. 2 is a side view thereof, showing our improved device partly in section. Fig. 3 is a detail view of a portion of our device.

The letter A designates one of the timbers constituting the door-frame, the same being of the usual or any approved construction, and extending upwardly and forming one side of the frame inclosing the transom; and the letter B designates the transom hinged at its lower edge, C, to the cross-beam D, connecting together the two uprights constituting the door-frame.

Attached securely by screws or otherwise, as may be desired, to the side of the transom is an angular plate, E, slotted in its outwardly-extending portion F, as more clearly seen in Fig. 2, and in which slot works one end of the crank-arm G, which arm extends from the shaft H, mounted in suitable bearings secured to the door-frame. In order to keep this shaft and its co-operating parts free from dirt and dust, and to make the appearance thereof more attractive to the eye, we cover them with a casing, J, and on the shaft H, opposite to the crank-arm, we mount the gear-wheel K, which intermeshes with the rack-bar L, formed on one end of the lifting-rod M, its lower end being screw-threaded, as shown at N. The lower portion, N, of this rod extends through the box O, in which is mounted the guiding-block P. This block P has its front face provided with a groove, Q, in which the lower portion of the rod lies, and said block, near its lower end, has a transverse cut or slot, Q', and in said slot is seated or located one of the intermeshing pinions, that portion of the block below said slot Q' being considerably recessed in order to admit of the collar of the said pinion extending therethrough.

An intermeshing gear-wheel, T, is mounted in the side of the box O, its shaft U having its outer end provided with a crank and handle, V, so that when motion is imparted to the shaft U by means of the crank the revolution of its miter wheel or pinion T revolves its fellow R, whose interior screw-threads, engaging with those upon the lower end, N, of the lifting-rod, cause the said rod to go up or down, according to the direction in which the pinion revolves, and in consequence thereof the pinion K and the rack-bar L cause the descent or ascent of the arm G and the transom to which the said arm is attached.

It will be observed that we can by our improved device hold the transom at whatever point we desire, and, so to speak, lock it in that position, for at whatever point it may be when we cease to revolve the crank-handle at that point exactly will it remain until the crank is again revolved.

Having thus fully described our invention, what we claim as new, and desire to secure by Letters Patent, is—

In a transom-lifter, the combination, with the lifting-rod and gear-wheels for giving motion to the same, of a holding and guiding block grooved on its front face to guide the rod, and having a slot at right angles thereto, in which the pinion is seated and re-

volves, and through which its collar descends, to and a casing to cover the said block.

In testimony whereof we affix our signatures in presence of two witnesses.

CHAS. HROMAS.
FRANK MACH.
